FIGS. 1-6 which are photos of various views of what is believed to be a prior art stretcher.

Primary Examiner—Kay H. Chin

Attorney, Agent, or Firm—Louis T. Isaf, P.C.**[57] CLAIM**

The ornamental design for a stretcher for transporting sick or injured human or animal, as shown and described.

DESCRIPTION

FIG. 1 is a top perspective view of a stretcher showing our new design in accordance with a first embodiment of the present invention;

FIG. 2 is a top plan view thereof;

FIG. 3 is a side elevational view thereof; the side opposite being a mirror image;

FIG. 4 is an end elevational view thereof;

FIG. 5 is an opposite end elevational view thereof;

FIG. 6 is a bottom plan view thereof;

FIG. 7 is a bottom perspective view thereof;

FIG. 8 is a cross-sectional view thereof taken along line 8—8 of FIG. 2;

FIG. 9 is a top perspective view of a second embodiment of the stretcher for transporting sick or injured human or animal; and,

FIG. 10 is a top plan view of FIG. 9, and the sides and end views are the same as the first embodiment shown in FIGS. 3 through 5.
